UNITED STATES PATENT OFFICE.

CHARLES H. SAMPSON, OF ROCHESTER, NEW YORK, ASSIGNEE TO PEERLESS CHECK PROTECTING COMPANY, OF ROCHESTER, NEW YORK, A CORPORATION OF NEW YORK.

INKING MECHANISM FOR PRINTING-MACHINES.

1,116,743.

Specification of Letters Patent. Patented Nov. 10, 1914.

Application filed December 4, 1913. Serial No. 804,611.

To all whom it may concern:

Be it known that I, CHARLES H. SAMPSON, of Rochester, in the county of Monroe and State of New York, have invented a certain 5 new and useful Improvement in Inking Mechanisms for Printing-Machines, which improvement is fully set forth in the following specification and shown in the accompanying drawings.

10 The present invention relates to inking mechanisms for a printing machine of the type having grooved type faces such as used in check protecting or check writing machines, and an object of the invention is to 15 so construct the inking roller that the latter will not be cut or worn out by contact with the type faces.

To this and other ends the invention consists in certain parts and combinations of 20 parts, all of which will be hereinafter described, the novel features being pointed out in the appended claims.

In the drawings: Figure 1 is a side view of a check writing machine like that shown 25 in my application #675,184 filed February 3rd, 1912, parts of the casing being broken away to illustrate the printing wheel and the inking roller which forms the subject of the present application; Fig. 2 is an enlarged sectional view of the inking roller and adjacent parts of the machine. Fig. 3 shows the roll in plan; and Fig. 4 shows the roll in longitudinal section and enlarged with a line of type in engagement therewith.

30 In my application for patent aforesaid, the printing wheel 1 is mounted to turn about an axis 2 and carries on its periphery the lines of type 3 projecting from the wheel and grooved for the purpose of coöoperating 40 with the serrated die mounted below the wheel and not shown. As this printing wheel rotates, the peripheral type are carried over an inking roller 4. In my application before mentioned, this roller had a 45 smooth cylindrical surface and, being made of fibrous material, it is soon cut or worn out by the teeth of the type wheel, the grooves of which run spirally about the wheel.

In this invention, the type wheel and 50 the inking roll are caused to rotate together so that the peripheral speeds of the two are the same, thus doing away with any cutting action of the grooved type on the inking roller. Preferably this result is effected by

providing portions on the periphery of the 55 inking roll to mesh with portions on the printing wheel or member. In this instance, these portions are in the form of parallel ribs extending longitudinally of the roller and projecting from the latter to engage between the projecting lines of type 3 on the printing wheel 1, the distances between these ribs 5 being substantially equal to the width of the lines of type so that the type engages the periphery of the inking roller between 60 the longitudinally-extending projections.

According to the above construction, when the printing wheel 1 rotates in either direction, the successive lines of type 3 thereon enter between successive projections 5 on 65 the inking roller to receive ink from said roller, this being due to the roller being driven by the interlocking connection between the longitudinally-extending projection and the lines of type. In this way, the 70 peripheral speed of the roller is the same as the peripheral speed of the printing wheel or member and consequently the serrated faces of the lines of type do not cut or saw on the periphery of the roller. That portion 75 of the roller engaged by the printing member does however conform to the shape of the type faces and become serrated. A further advantage of this inking roller is that it 80 coöperates with opposite edges of the lines 85 of type and gives a better inking of the type.

What I claim as my invention and desire to secure by Letters Patent is:

1. In a printing machine, the combination 90 with a printing wheel having lines of type projecting therefrom parallel with the axis of turning of the wheel, of an inking roller coöoperating with said printing wheel and having portions projecting therefrom to engage between the projecting lines of type 95 on the printing wheel to establish driving connection with the wheel.

2. In a printing machine of the class described, the combination with a movable 100 printing member, of an inking roller coöperating therewith and formed with projecting portions interlocking with the printing member to be turned by the latter.

CHARLES H. SAMPSON.
